WORK POSITIONING MEANS FOR HEELING MACHINES

Sidney H. Cook, Hannibal, Mo., assignor to United Shoe Machinery Corporation, Flemington, N. J., a corporation of New Jersey

Application September 22, 1950, Serial No. 186,193

4 Claims. (Cl. 1-32)

1

This invention relates to machines for attaching heels to shoes, and is illustrated herein as embodied in a heel holder adapted for use in a heelng machine of the type disclosed in United States Letters Patent No. 1,157,688, granted on October 26, 1915, upon an application of L. L. Glidden.

In the operation of the Glidden machine, two heel sections, such as a base and a top lift, are brought successively into register with the nailing die, and are attached to the shoe by successive nail driving operations. Such control of the heel sections is provided by a swinging holder having two compartments, one for each heel section, the holder being automatically swung, near the end of an operating cycle of the machine and after the heel base has been applied to the shoe, to bring the top lift into position for attachment to the shoe during the succeeding operation of the machine. This shifting movement of the heel holder is effected automatically by a normally energized spring loaded mechanism which is actuated at a predetermined point in the work releasing movement of the pressure applying mechanism.

For attaching the usual type of "rubber heel," which commonly comprises a thin leather base and a thicker rubber top lift, the machine may be fitted with a different form of heel holder which centers, at once, both heel sections over the die, and with respect to the shoe, the base and top lift being applied simultaneously to the shoe by a single operation of the nail driving mechanism. One such holder, as disclosed in the Reardon Patent No. 2,277,182, has a "heel ring" for holding the rubber top lift, and a set of fingers which engage the heel base at its sides and rear end, and centers it over the top lift. Because it is common to employ with a certain range of sizes of heel bases a top lift large enough for all such bases, the top lift usually overlaps the heel base slightly, and therefore, the fingers which engage the heel base. It now is evident that the fingers may interfere with the removal of the work from, or the insertion of a top lift into, the holder, if they are not separated to permit the top lift to pass freely between them at such times.

This difficulty is a voided by the Reardon invention which makes provision for automatically separating the fingers which engage the heel base, the nail driving movement of the nail driving mechanism being utilized for this purpose.

The object of the present invention is to simplify and improve upon the construction and operation of mechanism of this type, and to this end the invention provides, in a novel arrange-

2

ment, movable fingers in a heel holder adapted to center simultaneously two heel sections over the nailing die of a heelng machine of the Glidden type, and operating mechanism for the fingers which is actuated to separate and close the fingers automatically, in response to the operation of the pressure applying and nail loading mechanisms, respectively, of such a machine.

The illustrated operating emchanism for the heel holder comprises a spring loaded member which is releasably locked by a latch in its energized position, causing the fingers at this time to be positioned in their closed or operative relation. However, upon release of the latch, during the work releasing movement of the pressure applying mechanism, the fingers are automatically opened in order to facilitate removal of the work from the holder, and the supply of heel sections thereto for the succeeding heelng operation.

As is common in heelng machines of this type, the illustrated heel holder is mounted to slide to one side of the nailing die in response to movement over the die of the usual loader block from which a new supply of nails is delivered to the die. Then, as the loader block is moved back to its original position, the heel holder returns to its operative position under the influence of a spring. Each of these motions of the heel holder contributes materially to the operating cycle of the operating means for the fingers. That is, the operating mechanism for the heel holder is so constructed, in accordance with another feature of the invention, that sliding movement of the holder away from the die is utilized to reset the above-mentioned spring loaded member in its energized position. At this time the heel positioning fingers remain separated, but in response to the return movement of the heel holder to its operative position the same operating mechanism causes the fingers to be moved into their closed relation, whereby a heel section disposed between them is centered over the nailing die when the heel holder has been returned to its operative position.

These and other features of the invention will now be described in greater detail in the following specification, with reference to the accompanying drawings, and will be defined in the claims.

50 In the drawings,

Fig. 1 illustrates in plan one embodiment of my invention in a heelng machine;

Fig. 2 is a rear elevation of a part of the structure shown in Fig. 1;

Fig. 3 is a diagrammatical view in plan illus-

trating the operation of the means for opening and setting or closing of the heel positioning fingers provided by the invention; and

Fig. 4 is a side elevation of the upper part of the above-mentioned Glidden machine, in which the present invention is illustrated as embodied.

The heel holder illustrated herein is, in many respects, constructed and mounted like that of the machine disclosed in the above-mentioned Reardon Patent No. 2,277,182, and comprises the following parts which will be denoted by the same reference characters which have been applied to the corresponding parts of the Reardon structure. A carrier 18 is mounted to slide laterally of the machine on ways including a rod 20, and is arranged to receive a heel ring 24 having an opening which closely receives a rubber toplift L. A heel base H is positioned centrally over the lift L between a fork 44 and a pair of fingers 25, 26. The fingers are pivoted at 28 upon a support 29 which is mounted for adjustment upon the carrier 18 lengthwise of the fingers. The fingers are geared together at 27, so as to swing equally in opposite directions, and therefore, when in engagement with the opposite sides of the heel base H, they position the forward end of the heel base laterally with respect to the toplift L. The rear end of the heel base is similarly positioned with respect to the toplift by the fork 44, which also is yieldingly urged forwardly of the machine to hold the breast of the heel base in engagement with the hooked ends 42 of the fingers 25, 26 whereby the heel base is also positioned lengthwise thereof with respect to the toplift.

The carrier 18, as illustrated in Fig. 1, is at the righthand extremity of its travel upon the rod 20, the toplift and heel base being positioned at this time centrally over the nailing die 9 (Fig. 4) which is carried by a crosshead 10. The carrier is releasably locked in this position by a latch 52 (Fig. 1) which is integral with an arm 50 mounted to swing (at 50a) upon the carrier. As is well understood in this art, fastenings, such as nails, are supplied to the nailing die prior to a nailing operation from a loader 54 which is mounted to swing centrally over the nailing die. When the loader is thus moved by the operator it first engages the arm 50, operating the latch 52 to unlock the carrier and then, after the arm 50 engages the adjacent side of the carrier, it causes the carrier to be moved to the left along the rod 20 until the loader is alined with the nailing die. After the nails have been dropped into the die from the loader the latter is returned to its original position and is followed by the carrier 18 which is moved to the right by a spring (not shown) until it returns to its operative position.

Operating mechanism for the fingers 25, 26, provided by the present invention, is arranged to hold the fingers in their closed positions, prior to and during a nail driving operation, and later automatically to move the fingers away from the heel base, toward the end of a cycle of operation of the machine, in order to facilitate the removal of the work from the machine. Furthermore, the above-described lateral movement of the carrier is utilized both to reset the operating mechanism for a succeeding operation, and also to close the fingers into their operative positions.

The mechanism for thus operating the fingers 25, 26 comprises a rod 60 which is pivoted at 62 to an arm 64 which projects laterally from the finger 25. The rear end of the rod is slotted at 66 to receive a stud 68 carried by a crank arm

109 at the rear of the machine, this crank arm corresponding to that designated by the same reference character in Figs. 5 and 6 of the above-mentioned Glidden patent. When in its normal operative position the arm 109 is fixed and, through the stud 68 and rod 60, causes the fingers 25, 26 to be held against a heel base inserted therebetween. In order to bring the fingers into this desired relation to the heel base the length of the rod 60 may be adjusted by means of a turnbuckle 70. Toward the end of an operating cycle of the machine, and after a nail driving operation has been completed, the arm 109 swings rearwardly, first bringing the stud 68 to the rear end of the slot 66, and thereafter pulling the rod 60 rearwardly and causing the fingers 25, 26 to be separated until the finger 25 engages a stop 72 which is adjustably fixed to the left-hand side of the carrier 18 by a screw 74. The finished work may now be removed from the machine without interference between the fingers and any part of the heel. The mechanism next to be described and of which the crank arm 109 is a part, is the same as in the above-mentioned Glidden machine. Reference may be made to the Glidden patent for a complete understanding of the relation of this structure to the entire machine and its mode of operation.

The arm 109 is fixed to the upper end of a rock shaft 111 which is journaled in a bracket 112 fixed to the rear of the frame of the machine. One end of a spring 113, coiled about the rock shaft, is connected to the bracket 112, the other end being fixed to a collar on the lower end of the rock shaft. The spring is arranged constantly to urge the arm 109, as viewed in Fig. 1, in a clockwise direction. Such movement, however, of the crank arm 109 is normally prevented by a locking device which comprises, with an arm 114 integral with the arm 109, a beveled latch 115 adapted to be engaged by a keeper 118 mounted upon the upper end of an arm 119 which is fixed to the bracket 112. The latch 115 is mounted to slide vertically in the arm 114 and is normally held in its upward position, as shown in Fig. 2, by a spring 117. At the beginning and end of an operating cycle of the Glidden machine jacking pressure is applied and relieved, respectively, by mechanism including a rod 22 (Fig. 4) at the rear of the machine, a walking-beam 19, a plunger 14, and a swinging jack 12, the construction, arrangement and operation of which parts are fully described in the Glidden patent. For the purposes of the present disclosure it is sufficient to state that the clamping of the shoe against the nailing die 9 is accompanied by rising of the rod 22 from the position in which it is illustrated in Fig. 2, and later, with the release of clamping pressure, the rod returns downwardly to its illustrated position. This downward movement of the rod is utilized to release the latch 115 from the keeper 118, whereby the arm 119 is freed and the fingers 25, 26 are separated.

To this end, a bracket 121 fixed to the rod 22 has mounted therein, for horizontal sliding movement, a trip 122 which is yieldingly urged forward by a spring 123. When the rod 22 rises, the trip is moved into engagement with a beveled head 125 on the lower end of the latch 115, and is pushed rearwardly in the bracket 121 by the head 125 without having any further effect. As the trip 122 passes off the head 125 it springs forwardly over the head and later, when the rod 22 is lowered, engages the upper surface of the head

125 and pulls the latch 115 away from the keeper 118. The arm 109 now suddenly swings from its full line position (Figs. 1 and 3) to its dotted line position (Fig. 3) under the influence of the spring 113, pulling upon the rod 60 which opens the fingers 25, 26 into their dotted line position. The corresponding movement of the arm 114 causes the head 125 to be moved away from the trip 122, whereby the latch 115 again rises to its normal upper position under the influence of the spring 117. At this time a heel attaching operation will have just been completed.

In preparation for the next heelining operation the operator, after removing the finished work from the machine, swings the loader 54 to the left, causing the fingers 25, 26 (with the carrier 18) to be moved from their dotted line position (Fig. 3) to their dash line position. Such movement of the fingers, because it is parallel to the rod 20, causes the rod 60 to pull the arm 109 from its dotted line position to its full line position, when the latch 115 becomes re-engaged with the keeper 118 to hold the arm in the latter position. When the loader 54 is returned to its inoperative position, allowing the carrier 18 to return to its normal position over the nailing die, the rod 60 in being moved to the right (Fig. 3) moves rearwardly relatively to the stud 68 until the stud becomes seated in the forward end of the slot 66, this action taking place during the first part of the movement of the carrier 18 toward the right. During the remainder of such movement of the carrier the rod 60 pushes the arm 64 forwardly to move the fingers from their dash line position into their solid line position in which the fingers are properly spaced, assuming that the turnbuckle has been adjusted, to hold a heel base closely between them, and centered over the lift L.

Having described my invention, what I claim as new and desire to protect by Letters Patent of the United States is:

1. In a heel attaching machine having a nailing die, a jack for a shoe, and pressure applying mechanism operable to cause said jack and die to grip and release the shoe before and after a heelining operation respectively, in combination, a heel holder having oppositely movable fingers for centering a heel section with respect to said die, and means actuated by the work releasing movement of said pressure applying mechanism for retracting said fingers from the heel of the shoe.

2. In a heel attaching machine having a nailing die, a jack for a shoe, and pressure applying mechanism operable to cause said jack and die to grip and release the shoe before and after a heelining operation respectively, in combination, a heel holder having oppositely movable fingers mounted thereon for centering a heel section with respect to said nailing die, spring-loaded mechanism for operating said fingers, and means for latching said spring-loaded mechanism in its en-

ergized position whereby said fingers are positioned in their closed relation, said latching means being operable in response to the work releasing movement of said pressure applying means to release said spring-loaded mechanism whereby said fingers are opened.

3. In a heel attaching machine having a nailing die, a jack for a shoe, and pressure applying mechanism operable to cause said jack and die to grip and release the shoe before and after a heelining operation respectively, in combination, a heel holder having oppositely movable fingers mounted thereon for centering a heel section with respect to said nailing die, spring-loaded mechanism connected to said fingers for opening and closing them, and latching means for holding said spring-loaded mechanism in a predetermined energized position in which said fingers are positioned in their closed relation when said holder is in its operative position over said die, said latching means being operable in response to the work releasing movement of said pressure applying means to release said spring-loaded mechanism whereby said fingers are opened, said holder being mounted to move away from said die in opposition to the force exerted by said spring-loaded mechanism to return the latter to its energized position, said spring-loaded mechanism being constructed and arranged to return said fingers into their closed relation in response to movement of said holder into its operative position over said die.

4. In a heel attaching machine having a nailing die, a jack for a shoe, and pressure applying mechanism operable to cause said jack and die to grip and release the shoe before and after a heelining operation respectively, in combination, a heel holder having fingers for centering a heel section with respect to said nailing die, said fingers being mounted to swing upon said holder with equal and opposite movements, mechanism for opening and closing said fingers comprising a spring-loaded member and a link connecting said member and said fingers, a latch for holding said spring-loaded member in its energized position, and means operated by the work releasing movement of said pressure applying means to trip said latch permitting said spring-loaded member and link to open said fingers, said holder being mounted to slide in a direction to tension said link and pull said spring-loaded member into its energized position, said holder being movable in the opposite direction to shorten the distance to said spring-loaded member thereby to cause said link to close said fingers upon a heel section disposed between them and to center the heel section with respect to said die when said holder is returned to its operative position over said die.

SIDNEY H. COOK.
